UNITED STATES PATENT OFFICE.

JOHN J. FOGARTY, OF PHILADELPHIA, PENNSYLVANIA, ASSIGNOR TO JENKINS
INTERLOCK MANUFACTURING COMPANY, OF PHILADELPHIA, PENNSYLVANIA, A
CORPORATION OF PENNSYLVANIA.

INTERLOCKING DEVICE FOR ELEVATORS.

Application filed January 30, 1926. Serial No. 84,835.

My invention relates to an improvement in interlocking devices for elevators.

Heretofore it has been known to provide interlocking devices for elevators of such a nature that no one of the shaft-doors can be opened until the elevator car is at the level of a door; and upon the opening of a door, the elevator car cannot be moved until the door is again closed.

Various mechanisms have been developed for accomplishing this purpose and such mechanisms usually comprise shoes at the landings and a shoe carried by the car, which when the car is stopped at a landing, engages the landing shoe. The landing shoe and related mechanism are connected to the landing doors in such a manner that the doors cannot be opened unless the landing shoe is engaged by the car shoe, and upon the opening of the door, the landing shoe is advanced causing the car shoe to be retracted. The car shoe is so connected to the car control mechanism that when it is retracted the car controller will be locked, or if the elevator be operated by electricity, a cut out switch will be thrown.

Such mechanisms are usually applied to elevator installations having sliding doors and in which the doors are relatively close to the inside of the shaft, and in such installations the usual interlock mechanisms prove quite satisfactory. However, in installations where the landing doors are swung on hinges and more especially where the doors are positioned substantially back from the inside of the shaft, the known mechanisms are found to be not entirely satisfactory.

Now, it is the object of my invention to provide an improved interlocking mechanism of the character indicated, which will be adaptable for application to hinged doors and to doors which are positioned at substantial distance from the inside of the shaft.

Having now indicated in a general way the nature and purpose of my invention, I will proceed to a detailed description thereof with reference to the accompanying draw-

ings in which there is illustrated a preferred embodiment and in which:—

Fig. 1 is a partial view from inside of a shaft of an elevator door equipped with an interlock embodying my invention.

Fig. 2 is a sectional view taken at right angles to Figure 1.

Fig. 3 is a horizontal sectional view showing the interlock embodying my invention, in plan.

Fig. 4 is an enlarged sectional elevation looking from the left Figure 1 showing the interlock embodying my invention with the door in open position.

Fig. 5, is a view similar to that of Figure 4 with the door closed, but unlocked.

Fig. 6, is a view similar to that of Figure 4 with the door closed and locked.

In the several figures *a* indicates a view of an elevator shaft, provided with a landing *b*. The landing is of substantial depth and is closed by means of a door *c* swung on hinges *d*. The floor of the elevator car, adapted to be operated in the shaft is indicated at *e*.

On the wall of the shaft, just beneath the level of the landing, is secured a plate *f*, from which extends a pin *g* upon which is rotatably mounted a disc *h* having thereon a cam surface *i* and provided with a radial slot *j*. The disc *h* is held forward normally against the head of the pin *g* by means of a spring *k*. Beneath the disc *h* is mounted a stop *m* spaced from the plate and in line with a lug *n* carried by the disc, when disc *h* is in its normal forward position, in which position it is prevented from rotating.

The door *c* is provided with a vertical locking bolt *o* retained by a guide *p* and raised and lowered for engagement with and disengagement from a socket *q* in the landing by means of a lever *r* mounted on the door and connected with the bolt.

A rod *s* is rotatably mounted in bearings *t* on the landing and is provided at one end with an arm *u* provided with a lateral hole *v* for the reception of a pin *w* extending laterally through the bolt *o* adjacent to the lower end. The rear end of pin *w* serves as

a stop to limit the upper position of the bolt. The opposite end of rod *s* is bent around to form an arm *x* which is entered in the radial slot *j* in disc *h*. A spring *l* embraces rod *s* and is secured at one end to the rod and at the other to one of the bearings *t*. The spring tends to retain the arm in position for reception of pin *w* while the door is open.

Pivoted to plate *f* is a lever *y*, one end of which carries a shoe *z* and is held against the cam surface *i* by means of a spring *2* positioned between plate *f* and its other end.

Beneath the car floor *e* is slidably mounted a rod *3* carrying on its forward end a shoe *4* and connected at its rear end to one end of a pivoted lever *5*, the other end of which is acted on by a spring *6*, which tends to advance the shoe *4*.

The lever *5* engages the spring-pressed movable member *7* of a switch *8* adapted to connect and disconnect the operating current of the elevator car.

In operation, assuming the door to be closed and locked the parts will be in the position shown in Figure 6 and if the car be not at the landing, the rod *s*, which is connected to bolt *o*, through pin *w* and arm *u*, and to disc *h* through engagement of arm *x* in slot *j*, cannot be turned, since disc *h* cannot be rotated due to stop *m* in the path of which lug *n* lies because of the forward position of disc *h* under the influence of spring *h*. Hence the bolt cannot be raised out of socket *q* and the door cannot be opened.

If now the car be brought up to the level of the landing, shoe *4* engages shoe *z* and if lever *r* be turned, rod *s* will turn and through the engagement of arm *x* with disc *h* the disc will turn, and since lever *y* is held through the engagement of shoe *z* by shoe *4* the cam surface will act against lever *y* and the disc will be pressed backward against the action of spring *h* permitting lug *n* to pass behind stop *m*, as shown in Figure 4. In the further advance of the cam surface *i*, the lever *y* and the shoe *z* will be advanced and shoe *4* will be retracted thereby turning lever *5* against the action of spring *6* and actuating the member *7* to cut off the operating current.

On reclosing of the door the parts reverse their operation and lever *5* is turned by its spring *6* advancing shoe *4* and permitting member *7* to be actuated by its spring to connect the actuating current.

It is understood that my invention is not limited to the particular mechanism indicated and that it may be utilized in connection with various interlocking mechanism

such for example as lock a controller or other mechanism of an elevator as well as for operating a cut off switch such as described above.

I claim:

1. In an interlock for elevators the combination with a shaft, a landing and a car, of a landing door spaced from the interior of the shaft, interlocking mechanism on the car and shaft, adjacent the landing, a locking bolt for securing the door, a rod rotatably mounted on the landing and having an arm formed at one end and engaged with the interlocking mechanism on the shaft, the other end of said rod being adapted to be engaged with said bolt when the landing door is closed whereby when the interlocking mechanism on the shaft is engaged by the interlocking mechanism on the car, said rod may be rotated, permitting operation of the bolt and when said mechanisms are disengaged said rod is held from rotation by the interlocking mechanism on the shaft and operation of said bolt is prevented.

2. In an interlock for elevators the combination with a shaft, a landing and a car, of a landing door spaced from the interior of the shaft, interlocking mechanism on the car and shaft, adjacent the landing, a locking mechanism carried by the door and means engaged with the interlocking mechanism on the shaft and adapted to engage with said locking mechanism when the landing door is closed whereby when the interlocking mechanism on the shaft is engaged by the interlocking mechanism on the car, the locking mechanism may be operated and when the interlocking mechanisms are disengaged the locking mechanism may not be operated.

3. In an interlock for elevators the combination with a shaft, a landing and a car, of a swingably mounted landing door spaced from the interior of the shaft, interlocking mechanism on the car and in the shaft adjacent the landing, a locking bolt for securing the door, a rod on the landing engaged with the interlocking mechanism on the shaft and adapted to engage with said locking bolt when the landing door is closed whereby when the interlocking mechanism in the shaft is engaged by the interlocking mechanism on the car the locking bolt may be operated and when the said interlocking mechanisms are disengaged the bolt may not be operated.

In testimony of which invention, I have hereunto set my hand, at Philadelphia, Penna., on this 29th day of January, 1926.

JOHN J. FOGARTY.
